HENRY B. COOLEY, OF NEW BRITAIN, CONNECTICUT, ASSIGNOR TO THE AMERICAN PAPER GOODS COMPANY, OF MONTCLAIR, NEW JERSEY, A CORPORATION OF NEW JERSEY.

MACHINE FOR AFFIXING ATTACHMENTS TO ENVELOPS.

1,198,620.

Specification of Letters Patent. Patented Sept. 19, 1916.

Application filed February 7, 1913. Serial No. 746,798.

To all whom it may concern:

Be it known that I, HENRY B. COOLEY, a citizen of the United States, and a resident of New Britain, in the county of Hartford and State of Connecticut, have invented a new and Improved Machine for Affixing Attachments to Envelops, of which the following is a specification.

My invention relates more especially to machines for affixing fastening devices, by means of which the flaps are temporarily secured to close the openings in envelops, and an object of my invention, among others, is to provide a device of this class that shall be simple in its construction and method of operation, and particularly efficient in the character of work performed thereby.

One form of machine embodying my invention and in the construction and use of which the objects herein set out, as well as others, may be attained, is illustrated in the accompanying drawings, in which—

Figure 1 is a view in rear elevation of my improved machine, with parts broken away to show construction. Fig. 2 is a view in front elevation of the same, the lower part of the legs being broken off, and other parts being broken away to show construction. Fig. 3 is a top view of the machine with the aliner removed. Fig. 4 is a detail view on enlarged scale, partly in section, showing the construction of the plunger slides. Fig. 5 is a detail view showing the construction and operation of the rivet feed, parts being cut in section. Fig. 6 is a view in vertical section through the axis of the rivet carrier and looking from a point located at a right angle to the point of view of Fig. 5. Fig. 7 is a detail view showing the construction and arrangement of the toothed paper feed. Fig. 8 is a detail view showing the operation of the alining device. Fig. 9 is a detail view showing the means for retaining the rivet holder in place.

In the accompanying drawings the numeral 10 denotes legs supporting the bed 11 of the machine, which parts are of any suitable material, secured together in any desired manner. A driving shaft 12 is mounted in bearings at the back of the bed, and a driving pulley 13 is supported to rotate on the shaft, independently thereof, this pulley being arranged to receive a belt driven from any suitable source of power. A collar 14

is secured to the shaft and has a projection or projections engaging within a groove 15 in the hub at one side of the pulley, and the hub on the opposite side of said pulley is formed as a driving clutch member 16 having a tooth to engage a tooth on a driven clutch member 17, splined to the shaft 12 and movable longitudinally thereon, a spring 18 forcing the driven clutch member normally into engagement, this spring thrusting at one end against the bearing of the shaft and being so mounted that it will not interfere with the free rotation of the parts. The driven clutch member has a clutch disengaging cam 19 rigidly secured thereto with a stop shoulder 20 located to engage a stopping and starting pin 21 mounted for engaging and disengaging movement with said cam. An operating lever 22 is pivotally supported by the bed, and from a bar projecting therefrom, said lever being connected at one end with the stopping and starting pin, and at its other end with an actuating rod 23 connected at its lower end with a treadle 24 arranged to be operated by the foot of the user of the machine, a spring 25 secured at its upper end to the rod and at its lower end to the treadle drawing said parts toward each other and forcing the rod normally downward and causing the pin 21 to normally engage with the cam 19. When the treadle is pressed downward, the rod is forced upward, moving the pin 21 downward from engagement with the stop shoulder 20, thus permitting the spring 18 to force the clutch parts into engagement to effect rotation of the shaft 12.

The shaft 12 has bevel gears 26—27 secured at its opposite ends, which gears mesh with bevel gears on cross shafts 28—29 mounted in bearings on the bed 11. The cross shaft 28 has a stop cam 30 secured thereto to engage a shoe 31 on a friction stop 32 secured to the bed of the machine, said friction stop and stop cam being so constructed as to overcome the momentum of the machine and stop its movement when the clutch members 16 and 17 are disengaged, but to yield under the application of power to drive the machine when the clutch members are engaged, the cam at this time being forced from engagement with the stop.

A perforating and supporting slide 33 is

mounted for reciprocating movement in a slide-way 34 in the bed 11, the slide being held in place in any suitable manner, as by dovetail shaped projections engaging similarly shaped grooves in the slide-way, said projections and grooves not being shown as to this slide. This slide has a supporting plunger 35 rigidly secured thereto at one side and a washer forming plunger 36 secured at its opposite side, the latter being located in position to pass into a die opening 37 in a die plate 38 secured to the bed within an envelop receiving groove 39 formed therein, this die plate also having a plunger opening 40 to receive the plunger 35. The die opening 37 is of a diameter substantially equal to that of the washer to be formed therein, and a perforating plunger 41 is mounted for reciprocating movement axially in the washer forming plunger 36, this perforating plunger being of a size to produce the central opening in the washer formed by the plunger 36 and the die opening 37. A cap 42 is secured to the slide 33, and a slide actuating rod 43, pivotally attached to the cap and connected with an eccentric 44 secured to the shaft 28, is employed to reciprocate the slide, while a perforating plunger actuating rod 45, connected with an eccentric 46 secured to the shaft 28, operates the perforating plunger 41. The eccentric 44 is so located with respect to the eccentric 46 that it will advance the slide 33 slightly ahead of the perforating plunger 41, that is, the slide 33 reaches its advance movement toward the die plate 38 slightly before the perforating plunger 41 reaches its advance movement toward said plate.

A plunger supporting slide 47 is mounted in a slide-way 48 formed in the bed on the opposite side of the center thereof, from the slide-way 34, this slide being held in place in a manner similar to that above described, with respect to the slide 33, one of the dove-tailed shaped projections being shown in Fig. 6. This slide bears a washer forming plunger 49 having a central opening 50 in which, in some instances, a perforating plunger, similar to the plunger 41 and operated in like manner, may be located. In the form of machine herein shown, however, the perforating plunger is omitted and the plunger 49 is formed with an opening 51, constituting a die coöperating with the plunger 41 to produce the central openings in the washers.

A rivet securing plunger 52 is secured to the slide 47 on its opposite side from the washer forming plunger 49, the plunger 52 having a centrally located recess in which a rivet punch 53 is removably secured, projecting beyond the end of the plunger 52. This rivet punch is tubular and contains a rivet supporting pin 54 having a head 55 to retain it in place, a spring 56 being

located in the recess behind said pin and thrusting against it to force it normally outward.

A cap 57, secured to the plunger supporting slide 47, has a slide actuating rod 58 pivotally secured thereto, said rod being connected with an eccentric 59 secured to the cross shaft 29, by means of which eccentric the slide 47 is reciprocated. The cap has an opening therethrough registering with the opening 50 in the plunger 49, as clearly shown in Fig. 4 of the drawings. An adjusting screw 151 is mounted in the cap 57 and serves as a back stop to properly locate the rivet securing plunger 52 by determining its backward position in the slide, and a like or similar adjusting means may be employed to position such of the other plungers as may be desired, such adjusting means, however, not being shown herein. The shaft 29 has a hand wheel 60, (shown broken off in Fig. 3 of the drawings), by means of which the machine may be manually operated for the purpose of adjusting parts, or otherwise.

A rest 61 is located in the envelop receiving groove 39, upon which rest the envelops are placed on edge, and a supporting shoe 62 is secured at one end to a block 76 located in the slide way 48 and secured to the bed, the end of the shoe being pointed and extending along the groove 39, as clearly shown in Fig. 4, in position to project into an envelop, the end of the flap of which rests against an envelop stop 63 to be hereinafter described. This shoe 62 has an opening 64 to receive the washer forming plunger 49 by means of which opening and plunger washers to be affixed to the envelops are produced. A die 98 against which the rivets are headed by the punch 53 is secured to the shoe, and an envelop guide 99, in the form of a spring, is secured at one end to the shoe and projects to guide the envelop over the die 98 when the former is placed on the shoe, the guide yielding and its free end moving toward the shoe when the riveting takes place.

A supporting bar 65 is secured to the legs 10 at the front of the machine, and extends across the machine from side to side, a rest support 66 projecting upwardly from said bar at about its center, and having the envelop stop 63, that is adjustably supported on the bed 11, located over or resting against its upper end. A dovetail shaped rest guide 67 is secured to the rest support, the end of the rest 61 having a dovetail shaped groove to engage said guide, as shown in Fig. 4 of the drawings, this groove extending into a base 68 of the rest, which base is provided with a set screw (see Fig. 2) by means of which the rest may be adjustably secured in any desired position. Moistening boxes 69 are supported by the

oar 65 in position to receive moistening rolls 70 rotatably supported by the bar and projecting into the boxes that contain moistening material, as water. Tape supporting spools 71 are rotatably supported in proper position to deliver paper tapes having a dry adhesive on one side to the rolls 70 that moisten the adhesive, said tapes being of a width substantially equal to the diameter of the washers to be produced therefrom, these tapes 72 extending from the moistening rolls around guide rolls 73 rotatably mounted on the supporting bar 65 and positioned to press the tapes against the moistening rolls, tension bars 74, pivotally mounted on the bar 65 on the opposite side of the moistening rolls from the guide rolls 73, also holding the tapes down upon said moistening rolls. The tapes pass from the guide 20 rolls upward through tape openings 75 formed through the rest 61, and in the side of the block 76, back of the shoe 62, for the tape on the left-hand side of the machine, as seen in Fig. 4 of the drawings, said opening being formed in the side of the rest 61 and block 77 secured to the bed in the slide-way 34, and being located back of the die plate 38, for the tape on the right-hand side of the machine. The shafts of the moistening rolls have intermeshing gears 78 secured thereto outside of the moistening boxes, and one of the moistening roll shafts has a ratchet 79 secured thereto and engaged by a pawl 80 pivotally mounted on a pawl 85 actuating lever 81 rotatably supported on said shaft and connected by a rod 82 with a lever 83 pivotally supported on the bed, a curved bar 84 extending around the shaft 28 and pivotally secured to the lever 83, connecting said lever with an actuating rod 85 having its lower end forked to straddle the shaft 28 and bearing a roll 86 riding in contact with a cam 87 secured to the shaft 28 and by means of which said rod is reciprocated, thereby imparting a step by step movement to the moistening rolls through the medium of the connection just described.

A post 88 rises from the bed 11, this post being curved to locate a holder disk 89, rotatably supported at its upper end, over a rivet feed for supplying rivets to the mechanism. A holder 90 is secured to the disk 89, this holder being in the form of a wire upon which rivets 91 are placed. These rivets are of a form commonly used on envelopes and having a central tubular portion 92 with flexible arms 93 as shown in Fig. 5, which arms are adapted to be passed through an opening in the flap of an envelop and then bent backward upon themselves to hold the flap of the envelop in place. A guide 94 of trough shape to receive the rivet arms on one side of the tubular portion of the rivets located in the holder 90 is secured to the bracket 97. The

disk 89 may be rotated, as by means of a handle 95, to place the holder in a position diametrically opposite to that shown in Fig. 2, in which position the holder may be "loaded". After it has been "loaded", and before it is placed in position to feed, an aliner 96, pivotally mounted on the post 88, is employed to aline the rivet arms so that they will pass into the guide 94 when the holder is rotated to the feed position shown in Fig. 2. This aliner consists of an arm having a groove to receive and fit upon the central hub portion of the rivets, this arm being pivotally mounted on the post, as clearly shown in Fig. 8, it being of a length 80 to engage all of the rivets on the holder when swung upwardly from the position shown in Fig. 1, thus alining the rivets as above described.

The bracket 97 is secured to the block 76, rising therefrom to support a rivet carrier rotatably supported thereby in branches 100. This rivet carrier consists of a disk 101 having a hub 102 on which an annular disk 103 is secured, the disk 101 being also provided with journals 104 resting in bearings in the branches 100. A series of recesses 105 are formed radially within the carrier, one-half of each recess being formed in the disk 101 and the other half in the annular disk 103, the latter having slots 106 within which lugs 107 from rivet holding fingers 108 are located. The rivet holding fingers are each seated upon a spring 109 located in a recess in the hub, as clearly shown in Fig. 6 of the drawings. A track 110 is secured at its lower end in a groove in the block 76, this track curving over the bracket 97, as clearly shown in Fig. 5 and having a cam plate 111 secured at its upper end, and located in position to be engaged by the lugs 107 to move the rivet holding fingers radially inward in the carrier and permit them to pass under the end of the track 110, said lugs, however, being released from said cam and allowing the fingers to spring outward and enter the opening in the bottom rivet supported on the holder 90, as shown in Fig. 5, from which position, in the rotation of the carrier, the rivets are carried downwardly through a runway 112 consisting of a groove formed in the track 110. This groove is closed by a cover 113 which may, if desired, constitute an extension from the guide 94, this cover holding the rivets within the groove or runway as they travel downward therein. The movement of the fingers in a curved path withdraws them from the openings in the rivets at a certain point, from which the rivets fall on to a rivet rest 114 located at the lower end of the runway, the rivet being thus held in position for action of the riveting punch 53 operating through an opening 115 in the track 110 and against the die 98. The lower part of the runway 112 is closed 130

by a gate 116 mounted on a latch 117 pivotally supported on the block 76 and having a cam 118 located in the path of movement of the end of the plunger 52. This gate has an opening 119 in its edge to receive the hollow hub of the rivet, and the cam 118 is so formed that, as the riveting plunger 52 moves forward, it operates to move the gate backward at the proper time to allow the rivet to be carried by the pin 54 against the die 98, a spring 160 returning the latch 117 to its normal position, as shown in Fig. 4. A ratchet wheel 120 is secured to one of the journals of the carrier and is actuated by a pawl 121 supported on a pawl lever 122 mounted on the journal and connected by a rod 123 with an actuating arm 124 mounted on the slide 47. A pin from the arm 124 is located in a slot 125 in the rod, and a spring 126 connects the arm 124 with the lever 122 independently of said rod so that, should any obstruction present itself to movement of the carrier to feed rivets along the runway, the spring will permit the arm 124 to move and thus avoid injury of parts, the engagement of the pin with the slot positively moving the pawl to reengage the ratchet.

A tape feed support 127 rises from the bed 11 and has a foot 128 by means of which it is secured to the bed, this support having branches 129—130 at its upper end in which a tape feed shaft 131 is journaled. A tape feed operating lever 132 is rotatably mounted on the shaft and has a pawl engaging a ratchet 133 secured to the shaft. The lever 132 may be formed into a handle 134, and it is connected with the actuating rod 85 whereby the tape feed is actuated by means of the cam 87 on the shaft 28, from which it will be seen that the feed of the tape at the moistening device and at the upper part of the machine is simultaneous and from the same source. A feed wheel 135 is secured to the shaft 131, this wheel having teeth to engage with teeth on a feed wheel 136 loosely mounted on its shaft and also journaled in the branches 129—130, the teeth on one wheel pressing the paper tape into the space between the teeth on the other wheel. The shaft of the feed wheel 136 has cams 137 arranged to engage flanges 138 projecting from the branches of the support 127. This shaft is mounted in boxes 139 located in slots in the branches and pressed toward the feed wheel 135 by springs 140 seated upon the boxes and thrusting against a cap 141 secured to said branches. A handle 142 is secured to one of the cams or to the shaft, and by means of this handle, when the cams are caused to engage the flanges at their highest portions, the teeth of the feed wheels will be forced from engagement each with the other. Grooves 143 are formed in the feed wheels in which guides 144 extend,

these guides being secured to the structure within which the feeds are located and projecting into the grooves between the wheels to properly guide a tape thereinto.

The feed device just described is preferably used as a preliminary feed, and a main feed is employed to impart a regular step by step movement to the tape, at which time the toothed feed wheels will be disengaged as above described. This main or regular feed consists of a main feed wheel 145 mounted on a bracket 146 extending from the support 127, said main feed wheel having studs 147 arranged to engage the openings in the paper tape made by cutting the washers therefrom, each succeeding stud engaging the succeeding openings in the paper tape and thus imparting a regular step by step feed movement thereto. This main feed wheel is rotated as by means of an intermediate gear 148 mounted on a stud on said bracket, said gear meshing with a pinion 149 formed, in the construction herein shown, as a part of the feed wheel 135, said intermediate gear also meshing with a gear 150 mounted to drive the main feed wheel 145.

The operation of the device is as follows: It will be understood that in the first few operations of the machine the tapes 72 are engaged by the feed wheels 135—136 that draw upon the tape until a sufficient length is obtained to engage the studs 147 of the main feed wheel 145, after which the handle 142 is operated to disengage the feed wheel 136 from the feed wheel 135, by engagement of the cams 137 with the flanges 138.

The parts being in the positions shown in the figures of the drawings an envelop is placed upon the shoe 62 resting with its edge upon the rest 61 and with the end of the flap against the stop 63. Pressure upon the treadle 24, through the connecting mechanism, disengages the starting and stopping pin 21 from the cam 19 and the spring 18 forces the driven clutch member 17 into engagement with the driving clutch member 16 on the driving pulley 13 that is in continuous rotation. This rotates the driving shaft 12, and pressure upon the treadle 24 being released, the pin 21 is forced by the spring 25 into position to engage the cam 19, when it shall be rotated sufficiently, and forces the clutch parts out of engagement, thus stopping the operation of the machine, a single operation of all the parts taking place during a single rotation of the shaft 12, the stop 20 striking the pin 21.

The rotation of the shafts 28 and 29, through the intermeshing gears and connections, simultaneously moves the perforating and supporting slide 33 and the plunger supporting slide 47 toward each other, in which operation the supporting plunger 35 is moved through the opening 40 and against

the supporting shoe 62. At the same time the rivet securing plunger 52 is moved forward, the rivet supporting pin 54 passing into the central opening in the rivet which is located opposite said pin, resting upon the rivet stop 114. In this movement the end of the plunger 52 engages the cam 118 on the latch 117 moving the gate 116 from in front of the runway 112, which gate has, until this time, covered the runway at this point and held the rivet in place. The latter being now free to be moved forward is carried by the pin 54 against the die 98, the pin striking the die and retreating into the riveting punch 53 in the rivet securing plunger 52. The latter now engages the rivet, forces it through the back of the envelop and heads it on the die 98, securing the rivet in place. On the return movement the spring 56 will force the rivet supporting pin 54 into the position shown in the drawings and the spring (not shown) will return the latch 117 to the position shown, placing the gate in position to cover the runway to retain the next rivet which shall pass down the runway in position on the stop 114. In this movement of the plunger supporting slide 47 the washer forming plunger 49 is carried forward, engaging the tape 72 in the tape opening 75 on the left-hand side of the shoe 62, cutting a round disk from said tape by the action of the die opening 64, which disk is carried through the opening 64 against the flap of the envelop within the groove 39, the plunger 49 coming to rest with said disk lying against said flap.

The movement of the perforating and supporting slide 33 above described, moves the washer forming plunger 36 simultaneously with the plunger 49, the end of the plunger 36 engaging the tape in the opening 75 back of the die plate 38 and in connection with the die opening 37, forming another disk from said tape, carrying said disk through the opening 37 and against the opposite side of the flap of the envelop from that against which the disk first above described is brought to rest. In this operation the perforating plunger 41 is also carried forward by means of the eccentric 46, the plunger 41 reaching its forward position just after the slide 33 has reached its forward position. The slight dwell in the movement of the slides 33 and 47 caused by the eccentrics 44 and 59, "passing their centers" is made use of for the operation of the plunger 41 which, during such dwell, passes through the two disks and the envelop flap and in connection with the die opening 51 in the plunger 49, produces a hole, thus completing the formation of the washers, the piece taken out from the disks and the envelop flap passing into the opening 50 in the die 49, and eventually, by the successive location of the pieces within said opening, out through the

opening in the cap 57. The pressure of the dies at the end of the plungers 36 and 49 will cause the washers, which have been produced from the tapes having one side containing an adhesive moistened, to be firmly affixed to the opposite side of the envelop.

At the time of starting the operation of the machine, as above described, the end of a finger 108 will be located in the bottom rivet on the holder 90. The pawl 121 will, through the operation of the actuating arm 124 on the slide 47 and the connecting parts, rotate the rivet carrier a one step movement, removing the bottom rivet, and passing it along the runway, and in a further movement of the carrier the rivet will be located in position so that the pin will pass out of the opening in the rivet and allow it to drop on to the stop 114. As one rivet is being removed from the holder 90, the lug 107 on the next succeeding plunger engages the cam plate 111, drawing the finger radially inward so that it may pass under the end of the track 110, and just as soon as the lug disengages from said cam plate the finger snaps outwardly into the opening in the rivet.

The rotation of the cam 87 by the shaft 28, through the actuating rod 85 and lever 83 and connecting parts, will simultaneously operate the ratchet feed to impart a step by step movement to the moistening rolls 70 and to the main feed wheel 145, thus imparting a step by step movement to the paper tapes which, being passed through the water or like moistening material within the boxes 69, are properly moistened to be affixed to the envelop flap hereinabove described.

In placing the rivets upon the holder 90, the handle 95 is operated to rotate the holder disk 89, thus placing the holder 90 in a diametrically opposite position from that shown in the figures, in which position, by means of a "loader" or otherwise, the rivets are placed upon the holder. The aliner 96 is now swung upwardly projecting the hubs 92 of the rivets into the groove in the aliner, thus bringing all of the arms 93 into alignment, after which, the aliner being moved to its normal position, as shown in Fig. 1, the holder is returned to its normal position, as shown in Fig. 2, and the arms of the rivets being thus aligned will properly enter the groove in the guide 94.

It will be understood that if it is desired to affix a washer to one side of the envelop flap only, this operation may take place simply by omitting a paper tape in one of the openings 75 on that side of the flap to which it is desired the washer shall not be affixed.

While I have shown and described herein a form of mechanism employed by me for effecting the desired results, it will be under-

stood that this construction may be changed without departing from the spirit and intent of the invention which is, therefore, not necessarily limited to the precise construction herein shown and described.

10 The holder disk 89 is yieldingly held in different positions, and especially in its feeding position by means of a spring seated pin 152 and having a beveled end engaging recess 153 to resiliently hold the disk. By application of some force to the handle 95 the disk may be disengaged and moved to a different position.

I claim:

15 1. A bed having a groove therein, a shoe supported by the bed, an envelop rest underlying the shoe, the latter having an opening and an anvil, a slide mounted in said groove for reciprocating movement with respect to 20 said shoe, a block secured in said groove, a plural number of plungers projecting from said slide through openings in said block, one of said plungers being adapted to coöperate with the opening in the shoe 25 and the other with the anvil thereon, and means for operating the plungers.

30 2. A bed having a slideway therein, blocks located in said slideway and spaced apart to provide an opening, an envelop rest located underneath said opening, a shoe adapted to receive an envelop and secured to one of said blocks and projecting within said opening, said latter block having a groove constituting an opening for a paper 35 tape behind said shoe, a die plate secured to the opposite block that has a groove forming an opening for a paper tape behind said plate, plungers slidably mounted to operate through openings in said die plate and 40 shoe and upon said envelop, a riveting anvil located on said shoe, and a slidably mounted plunger adapted to operate in connection with said anvil.

45 3. A bed having a groove in its upper surface, a block located in said groove, a die plate secured to the face of said block, a slide mounted for reciprocating movement in said groove, means for operating the slide, a plunger secured to said slide 50 for movement in an opening in said block, a second plunger secured to the slide for movement in another opening in said block, and an anvil to coöperate with the second plunger.

55 4. A bed having a groove in its upper surface, blocks located in said groove and spaced apart to form an opening, a shoe adapted to receive an envelop and secured to one of said blocks and projecting along 60 said opening, an envelop rest located underneath said opening, a slide located in said groove back of each of said blocks, plungers secured to said slides to operate in connection with die openings on the facing surfaces of said blocks, an anvil secured to said shoe,

and a plunger secured to one of said slides to operate in connection with said anvil.

5. A bed having a groove in its upper surface, blocks secured in said groove and spaced apart to form an opening, a shoe 70 adapted to receive an envelop and projecting from one of said blocks and having a die opening, an anvil secured to said shoe, a die on the face of the other block, a slide mounted in said groove, plungers projecting from said slide and movable through openings in a block, one of said plungers to coöperate with said die opening and the other with said anvil, a slide located in the groove back of the other block, a plural 80 number of plungers secured to the last mentioned slide to operate through openings in the die block, an envelop rest underlying said shoe, and means for operating the slides.

6. A reciprocating slide with means for operating it, a member having a die opening therein, a plunger secured to said slide to coöperate with said die opening in effecting a cutting operation, a second plunger 90 movably mounted in the first plunger, means for operating the second plunger, means having a die opening to coöperate with the second plunger in effecting a cutting operation, another plunger secured to 95 said slide, a shoe to receive an envelop to be operated upon by said plungers and having an anvil to coöperate with the last mentioned plunger, and a rest to support an envelop in connection with said 100 shoe.

7. A slide, means for operating said slide, a plunger secured to the slide, a second plunger located in the first mentioned plunger, means for operating the second plunger, a third plunger secured to said slide, a shoe to receive an envelop to be operated upon by said first and second plungers, an envelop rest underlying the shoe and an 105 anvil secured to the shoe in position to co- 110 operate with the third plunger.

8. An envelop rest, a shoe projecting to support an envelop located on said rest, said shoe having a die opening, a plunger movably supported to coöperate with said 115 opening in cutting a piece to be attached to the envelop, a riveting die secured to the shoe, a plunger movably mounted to support said die in the riveting operation, and a riveting plunger movably mounted to 120 affix a rivet to said envelop.

9. An envelop rest, a shoe supported to receive an envelop on said rest, said shoe having a die opening, a riveting die supported by said shoe, a plunger movably 125 mounted to coöperate with said die in affixing a rivet to an envelop, a slide movably mounted, a plunger secured to said slide to coöperate with said die opening to cut a piece to be affixed to an envelop. and a 130

plunger secured to said slide to support said riveting die in the riveting operation.

10. A support for an envelop, means for supplying to said envelop a piece cut from a tape, toothed members to receive the free end of the tape to impart feed movement thereto, means for operating said toothed members, a second feed to engage said tape for feeding movement, and means for separating the toothed members.

11. A support for an envelop, moistening devices to receive a tape and moisten the gummed side thereof, a feed for said moistening devices, means for cutting a piece from said tape and applying it to said envelop, a feed device to engage the free end of said tape, and a single feed operating mechanism connected with both of said feed devices.

20 12. An envelop support, means for cutting a piece from a paper tape and for affixing it to said envelop, a toothed feed mechanism to engage said tape, said mechanism including toothed wheels one of which is mounted in slidable bearings, a cam attached to one of said wheels, a rest for said cam, and means for rotating the cam on said rest to slide said bearings to separate said toothed members.

30 13. A rest for an envelop, a bed, a die plate having a die opening, slides mounted for reciprocating movement toward and from each other on said bed, a plunger secured to each of said slides, one of said plungers having a die opening, and the other arranged to pass through the opening in said die plate and into said die opening in said plunger, a plunger mounted in the last mentioned plunger and provided with means for operating it independently of said slide, a shoe located above said rest to receive an envelop to be operated upon, an anvil mounted on said shoe, a plunger secured to one of said slides to act in coöperation with said anvil, and means for operating the slides.

40 14. A die plate having a die opening therein and a tape opening behind the die plate, means for feeding a tape through said tape opening, a plunger having a die opening and adapted to coöperate with said die opening in said plate in cutting a piece from said tape, a slide to which said plunger is secured, means for operating the slide, a second plunger mounted in the first mentioned plunger, means for operating the second plunger, means coöoperating with the second plunger to effect its cutting operation, an envelop rest, a shoe located above said rest to receive an envelop to be operated upon by said plungers and having an anvil, and a third plunger that is secured to said slide to coöperate with said anvil.

50 15. A support for an envelop, means for supplying to said envelop a piece cut from a tape, a preliminary feed to receive the free

end of the tape to impart feed movement thereto, means for operating said feed, means for rendering said feed inoperative, and a second feed to engage said tape for feeding movement.

70 16. An envelop rest, a shoe supported above said rest and having a die opening and an anvil, a reciprocating slide, a plunger secured to the slide to coöperate with said die opening, a second plunger secured to the slide to coöperate with said anvil, means for feeding rivets to said anvil, a gate to hold said rivets, and means for operating said gate through the movement of the slide.

17. An envelop rest, a shoe supported above said rest and having a die opening, an anvil, a reciprocating slide, a plunger secured to said slide to coöperate with said die opening, a second plunger secured to said slide to coöperate with said anvil, means for supplying rivets to said anvil, a gate normally located opposite the anvil to retain said rivets, and means for effecting operation of said gate through the movement of said slide.

80 18. An envelop rest, a shoe located above said rest and having a die opening, an anvil, a reciprocating slide, a plunger secured to said slide to coöperate with said die opening, a second plunger secured to the slide to coöperate with said anvil, a latch pivotally mounted in the path of movement of said slide, means for supplying rivets to said anvil, and a gate secured to said latch to retain the rivets in position opposite said anvil.

90 19. A bed having a groove therein and an opening extending across said groove, a shoe supported by the bed in said opening, said shoe having means to operate upon an envelop, blocks secured in said groove upon opposite sides of said shoe, slides secured in said groove on opposite sides of said shoe, a plunger projecting from each slide through a block to operate upon an envelop, and means for operating the plungers.

100 20. A bed having a groove therein with an opening extending across said groove, a shoe located in said opening and having means to operate upon an envelop, a rest underlying the shoe and adapted to support an envelop received upon said shoe, blocks mounted in said groove upon opposite sides of the opening, slides located in said groove upon opposite sides of the shoe, plungers projecting from the slides through said blocks and adapted to operate upon an envelop, and means for operating the slides.

110 21. A bed having a groove in its surface, blocks located in said groove and spaced apart to provide an opening between them, said blocks having openings therethrough, die plates located at the mouths of said openings, slides located in the grooves back of the blocks, plungers secured to each of said

slides and projecting through said openings in the blocks, one of which plungers has a central opening, another plunger located in one of the first mentioned plungers and adapted to operate through said central opening in another plunger, and means for operating all of said plungers.

22. A bed having a groove in its surface, blocks located in said groove and spaced apart to provide an opening between them, one of said blocks having a projecting part on the side facing the other block and spaced from said other block to permit entry of an

envelop flap between the blocks, a shoe secured to said projection and extending between the blocks providing an opening between the shoe and the block to which it is secured, slides located in said groove back of the blocks, means carried by the slides to operate upon an envelop against said shoe, and means for operating the slides.
